POLE OR TOWER PLATFORM

Roy C. Barnes, Long Beach, Calif., assignor of
one-half to William J. Frazier, Manhattan
Beach, Calif.

Application July 6, 1938, Serial No. 217,772

2 Claims. (Cl. 304—28)

This invention appertains to new and useful improvements in platforms especially adapted for use by linemen on poles and towers.

The principal object of the present invention is to provide a platform which can be readily mounted and which will be sturdy and safe in use.

Another important object of the invention is to provide a platform of the character stated which is constructed in such a manner as to be adaptable to various shapes and sizes of poles and towers.

These and other important objects and advantages of the invention will become apparent to the reader of the following specification.

In the drawings—

Figure 1 represents a sectional view taken substantially on a line 1—1 of Figure 2.

Figure 2 is a side elevational view of the structure shown in Figure 1.

Figure 3 is a sectional view taken substantially on a line 3—3 of Figure 1.

Figure 4 is a sectional view taken substantially on a line 4—4 of Figure 3.

Figure 5 is a front elevational view of the platform, with the chain clamp removed.

Referring to the drawings, wherein like numerals designate like parts, it can be seen that the numeral 5 represents the platform proper preferably covered by rubber pads 6. Numeral 7 represents the head portion of the platform and this is preferably constructed of metal and bifurcated on a horizontal plane to afford the upper and lower furcations 8—9 spaced apart to accommodate the clamping chain 10.

The pole or tower engageable end of the head 7 is of V-shape and stepped as at 11 so as to accommodate girders, angle irons or round holes of various sizes. The burrs 12—12 on the forward corners of the head 7 are used when the platform is engaged with a pole, preferably wooden poles, that cannot be gripped by the stepped V-shaped cut.

A bifurcated lug 13 on one side of the head 7 is intended to receive the T-member 14 at one end of the aforementioned chain 10. This is the anchoring means for one end of the chain, while the other end portion of the chain extends between the furcations 8 and 9 to connect to the screw shaft 15 at one end thereof. This screw shaft at its opposite end portion extends through the boss 16 on the same side of the head 7 with the lug 13. Numeral 17 represents a round nut engaged on the threaded shaft 15 and being rotatable against the boss 16 to feed the shaft 15 in forward or reverse direction. This nut 17 has a handle 18 which has a

yoke 19 embracing the nut 17 and being pivotally connected thereto.

Obviously, by disposing the chain 10 around the tower member 20 and engaging the T 14 with the lug 13, the platform can be held until the chain is firmly clamped in position by feeding the nut 17 inwardly on the shaft 15, thus drawing the shaft 15 through the boss 16 and pulling tightly on the chain 10.

The head 7 is provided with a pair of outwardly extending upper legs 21—21 and a pair of somewhat longer lower legs 22—22. Between these upper and lower legs 22—22 and 21—21 is disposed the forward portion of the platform 5 and bolt members 23 are disposed through the legs and platform for securely fastening the platform to the head 7.

A pair of brace members 24—24 extend forwardly from the free end portions of the legs 22—22 and in downwardly diverged relation with respect to the head 7 and are braced at their lower ends by the V-shaped pole or tower engageable member 25 which has its indented side stepped as at 26. The lower ends of the brace members 24 are provided with spurs 27 which are used in the same capacity as the spurs 12—12.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is—

1. A platform of the character described comprising a supporting structure having an upright engageable head portion, and a clamp chain mounted at its upright engageable end for embracing an upright and holding a support thereto, and a downwardly extending upright engageable brace on the support said brace including a horizontally elongated member, and spurs on the ends thereof.

2. A platform of the character described comprising a supporting structure having an upright engageable head portion, and a clamp chain mounted at its upright engageable end for embracing an upright and holding a support thereto, said support being divided into a head portion and a seat portion said head portion provided with vertically spaced horizontally disposed leg members, said seat portion having one end thereof disposed between said leg members and securing means between the leg members and the seat portion.

ROY C. BARNES.
